UNITED STATES PATENT OFFICE.

JOHN G. LYMAN, OF PHILADELPHIA, PENNSYLVANIA.

DESIGN FOR A BOTTLE.

No. 40,020.

Specification for Design.

Patented June 1, 1909.

Application filed April 8, 1909. Serial No. 488,774. Term of patent 7 years.

To all whom it may concern:

Be it known that I, JOHN G. LYMAN, a citizen of the United States, residing in the city and county of Philadelphia, State of Pennsylvania, have invented a new, original, and ornamental Design for Bottles, of which the following is a specification, reference being had to the accompanying drawing, forming part thereof.

Figure 1 is a side elevation of a bottle. Fig. 2 is a top plan view of the same.

I claim:

The ornamental design for a bottle, as shown.

JOHN G. LYMAN.
